UNITED STATES PATENT OFFICE

2,605,922

BOX AND MATERIAL FOR USE THEREIN

Charles D. Mattingly, Wichita, Kans., assignor of
one-half to J. Carroll Cuffman, Malvern, Ark.

Application May 25, 1949, Serial No. 95,337

6 Claims. (Cl. 217—16)

1

My invention relates to an improved box and a material for use therein.

In accordance with the present invention an improved inexpensive box construction is achieved without sacrificing strength or requiring additional storage space. Moreover, the box may be constructed of low cost readily available materials and is simply and rapidly assembled. Further in accordance with the present invention an improved box-forming material capable of being easily handled and stored is provided.

More particularly, the box of the present invention uses a corrugated cardboard side-defining material having spaced transverse support members. Reinforcing wires extend longitudinally of the cardboard sheet and in criss-cross relation on each panel thereof. These wires overhang the edges of the cardboard sheet in the regions adjacent the boundaries of the side panels.

The cardboard material, bearing the transverse supports and reinforcing wires, may be rolled for purposes of storage and cut off at will during assembling operations.

When the box is assembled, the side-forming material is unrolled and wrapped between a pair of spaced cooperating polygonal top and bottom defining members. The criss-cross reinforcing wires are then wrapped about themselves to fit snugly against the corners of the top and bottom members and hold the same in position.

It is therefore a general object of the present invention to provide an improved box construction.

Another object of the present invention is to provide an improved side-defining material for use in constructing boxes.

A further object of the present invention is to provide an improved side-defining material for use in constructing boxes and capable of being rolled up or folded for storage and adapted to be cut to form boxes of any desired number of sides.

Another object of the present invention is to provide a light-weight, inexpensive box construction having a high degree of resistance to stacking and other stresses encountered in use.

Still another object of the present invention is to provide a box defining a good advertising space.

Yet another object of the present invention is to provide an improved box having imperforate side walls.

The novel features which I believe to be characteristic of my invention are set forth with particularity in the appended claims. My in-

vention itself, both as to its organization and mode of operation, together with further objects and advantages thereof, may best be understood by reference to the following description taken in connection with the accompanying drawings, in which:

Figure 1 is a plan view of the side-forming material of the present invention as cut to form a four-sided box;

10 Figure 2 is a perspective view of a box constructed in accordance with the present invention;

15 Figure 3 is a cross-sectional view of the box of Figure 2 taken immediately below the top member as indicated by the lines 3—3, Figure 2;

20 Figures 4 and 5 are views respectively of a top member for use in the box of the present invention and a side-defining member formed in a tube to receive the top member, and;

25 Figure 6 is a fragmentary cross-sectional view through axis 6—6, Figure 2.

As shown in Figure 1, the side-defining material of the present invention is formed of a strip of corrugated cardboard 10. This strip is wrapped to form a tube as shown in Figure 5 when it is desired to form a box. The corrugations 10a, Figure 5, of the cardboard sheet 10 are oriented transversely of the length of the strip and face inwardly on the tube, thus providing a smooth exterior surface capable of receiving printing.

The strip 10 is affixed to a series of pairs of transverse support members or bars 12. Each pair of these members is located at the corner of the resultant box as shown in Figure 5. The portion of the cardboard 10 extending between each pair of support members defines a panel forming a side of the resultant box. The portions of the cardboard between the support members of each pair are folded in the final box construction to define edges.

The transverse support members 12 are attached to the cardboard 10 by U-shaped fasteners 12a, each fastener being driven through the cardboard into the corresponding support member.

The cardboard strip 10 also receives a plurality of longitudinally extending reinforcing wires 14. These are affixed to the cardboard by U-shaped staples 14a bent over as required to achieve a snug attachment.

Longitudinal wires 14 are additionally attached to the cardboard 10 by the staples 14c which extend through bars 12.

55 In addition to the longitudinal reinforcing

wires 14, a pair of criss-crossed wires 16 and 18 extend along the cardboard sheet 10. Each of these wires extends diagonally across each panel defined by sheet 10, and in opposite directions across the successive panels. The wires 16 and 18 are oriented in criss-cross relation so that they extend between the opposed pairs of corners of each panel.

Each of the criss-crossed wires 16 and 18 extends beyond the width of the sheet 10 in the region between adjacent panels. These regions are indicated at 16a and 18a, Figure 1, and form triangularly shaped sections. As will be described in further detail hereafter, these sections overlie the corners of the top and bottom members of the box to retain these members in place.

Criss-crossed wires 16 and 18 are attached to the sheet 10 by the staples 16b and 18b, respectively.

When the box is assembled, the ends of wires 14 are wrapped together as at 14b, Figure 5, to form a box-defining tube. Top member 20 and bottom member 22 are then fitted in place. Each of these members has four outside slats 24, Figure 4, adapted to fit snugly against the cardboard 10 as indicated at Figure 6. The slats oriented in one direction extend beyond the other slats at 24a to be received on the upper edge of the cardboard 10 as shown in Figure 6. A cross slat 26 is provided to maintain the square shape of the top and bottom members.

As seen best in Figure 6, the lower slats 24 also rest on the ends of the corner-defining transverse members 12 affixed to the cardboard sheet. These transverse members take up load when the top and bottom members are urged towards each other.

In assembling the box, the ends of criss-cross wires 16 and 18 are twisted together as shown at 16c and 18c, Figure 5. This defines a loop at each corner of the box. After the top and bottom members are placed in position, the loops over each corner are twisted together as shown at Figure 2 until the wire rests snugly against the corners of the box. The wires 16 and 18 consequently resist any forces tending to separate the top and bottom members 20 and 22.

Assembly of the box of the present invention is simple and inexpensive. The cardboard material 10 can be made up in long rolled sections to which the wires 14, 16 and 18 are affixed and the members 12 are attached. The length necessary for the desired box can then be cut off and formed into a tube as shown in Figure 5. The top and bottom members 20 and 22 are then placed in position and the sections 16a and 18a twisted tight to form a snug fit against the corners of the top and bottom members. If the object to be carried is heavy, it may be mounted on bottom member 22 and the tube of Figure 5 slipped over the object to form a box. Manufacture of the side-forming material shown in Figure 1 can be accomplished simply and economically by automatic machinery adapted for this purpose. Since the material is readily shipped and stored in the coiled or rolled condition, a single installation for this purpose may serve many box users.

The twisting operation required to force the extending loops 16a and 18a against the corners of the box can be facilitated by providing a suitable tool for the purpose.

While I have shown criss-crossed reinforcing members 16 and 18 as round wires, other suitable material, such as steel strap may be used. These

members extend diagonally across each panel in proper direction to take up the stress associated with forces tending to collapse the box by shearing the top member 20 relative to the bottom member 22.

The transverse support members take up most of the compressive force exerted between the top member 20 and the bottom member 22. However, the corrugations 10a of the cardboard 10 supplement these members. Force of this type may, for example, result from stacking boxes.

In addition to forming impervious side panels, the cardboard sheet 10 forms a useful surface for advertising. The advertising may, for example, be printed on the roll of corrugated cardboard before the side-forming material of Figure 1 is made.

The transverse support members 12 are readily made because they are of identical dimensions. A convenient material for this purpose is $\frac{1}{4}$ " rotary cut veneer.

The box of the present invention has proven highly successful. The cost is about 50 percent less than conventional crates. It is simple and easy to manufacture and assemble and light in weight. Yet it has ample strength to resist all the forces applied during handling and storage.

The box shown in the figures is of cubical configuration. It will, of course, be evident that other shapes may be formed and that the bottom and top members may be of any cooperating polygonal shapes.

While I have shown and described a particular embodiment of my invention, it will of course be understood that I do not wish to be limited thereto since I intend by the appended claims to cover all modifications and alternative constructions as fall within the true spirit and scope of my invention.

What I claim as new and desire to secure by Letters Patent of the United States is:

1. A coilable assembly for use in forming the side walls of shipping containers characterized by being fastenable to preformed top and bottom members to provide at least one complete shipping container with the aid of only a pair of pliers, comprising an elongated sheet of flexible cardboard having spaced transverse support bars affixed to one side thereof to provide an array of adjacent panels, and a pair of reinforcing wires extending diagonally in opposite directions across successive panels, the wires being in criss-crossed relation on the successive panels and on the side opposite the support bars, each wire overhanging the sheet in the region adjacent each pair of support bars, whereby when said sheet or a portion thereof is folded to form a polygonal tube having said panels as side walls and with said support bars on the interior surface, said overhanging wire portions can be twisted together to secure said pre-formed top and bottom members to said tube across the corners thereof.

2. A coilable assembly for use in forming the side walls of shipping containers characterized by being fastenable to preformed top and bottom members to provide at least one complete shipping container with the aid of only a pair of pliers, comprising an elongated sheet of corrugated cardboard having parallel sides and evenly spaced pairs of support bars affixed to one side of said sheet so as to extend thereacross at right angles to said parallel sides and thereby providing an array of adjacent panels, and a pair of pliable reinforcing wires extending diagonally in

opposite directions across successive panels, the wires being in criss-crossed relation on the successive panels and on the side opposite the support bars, said wire forming loops overhanging the sheet where they cross the ends of said support bars, whereby when said sheet is folded to form a polygonal tube with said panels as side walls and with said support bars on the interior surface, said wire loops are caused to overhang the corners of said tube so that they can be twisted together to secure said pre-formed top and bottom members to said tube.

3. The assembly of claim 1 wherein said sheet has secured thereto a plurality of longitudinal reinforcing members on the same side as said diagonal reinforcing wires, said longitudinal reinforcing members being formed of flexible material so that said sheet can be coiled.

4. The assembly of claim 2 wherein said sheet has secured thereto a plurality of longitudinal reinforcing members on the same side as said diagonal reinforcing wires, said longitudinal reinforcing members being formed of flexible material so that said sheet can be coiled.

5. A shipping container, comprising a polygonal tube having open ends and a plurality of flat side panels, said tube being composed of a flexible cardboard, transverse support bars affixed to the interior surface of said panels at the corners thereof, closure members of the same dimensions as the open ends of said tube seated on the ends of said tube, and a pair of reinforcing wires extending diagonally in opposite directions across successive panels, the wires being in criss-crossed relation on the outside surface of the successive panels, said wires having portions lying across the corners of said tube and the corners of said closure members, said portions being twisted together to clamp said closure members to said tube, whereby said closure mem- 40

bers can be removed to open said shipping container by merely untwisting the wire portions extending over the corners of said tube and closure members.

5. A shipping container, comprising a polygonal tube having open ends and a plurality of flat side panels, said tube being composed of a sheet of corrugated cardboard, pairs of transverse support bars affixed to the interior surfaces of said panels at the corners thereof, closure members on the ends of said tube, and a pair of reinforcing wires extending diagonally in opposite directions across successive panels, the wires being in criss-crossed relation on the outside surface of the successive panels, said wires having portions lying across the corners of said tube and the corners of said closure members, said portions being twisted together to clamp said closure members to said tube, whereby said closure members can be removed to open said shipping container by merely untwisting the wire portions extending over the corners of said tube and closure members.
